TELEVISION APPARATUS

Raymond S. Yoder, Chicago, Ill., assignor to
 Galvin Manufacturing Corporation, Chicago,
 Ill., a corporation of Illinois

Application June 26, 1941, Serial No. 399,763

9 Claims. (Cl. 178—7.5)

This invention relates generally to television apparatus and in particular to a housing and supporting means for the picture means of television receiving apparatus.

In television receiving apparatus of the prior art it is usual to employ picture or scanning tubes in providing for a visual display of the televised material. These tubes are usually about sixteen to twenty-four inches long, with the picture face or screen being arranged at one end thereof. It is evident, therefore, that the picture face is most conveniently viewed when the tube is in a substantially longitudinal position in its associated cabinet or supporting structure, with the picture face arranged at the cabinet front. However, the relatively long length of the tube requires a cabinet of considerable depth to completely enclose the tube in this position whereby to appreciably increase its size and bulk, as compared to the usual console radio cabinet, and hence its cost. In attempts to overcome this increase in cabinet size, the picture tubes have been arranged in a substantially vertical position within the cabinets with the picture face arranged in a top wall or panel of the cabinet. In order to have the representations on the picture screen visible from a position in front of the cabinet, a top lid or cover for the cabinet is provided having a mirror or like reflecting surface on the underside thereof in operative association with the picture face. Although this arrangement of the picture tube in the cabinet appreciably reduced the size of the cabinet, particularly as to depth, it was not entirely satisfactory because of the indirect viewing of the representations on the picture screen, and the limited view of the reflecting mirror over a rather restricted radius, as well as longitudinal level, from a position before the cabinet. Also a mirror utilized in this manner reduces the illuminating effect of the picture screen, and further increases the cost of the television apparatus.

It is an object of this invention, therefore, to provide improved television apparatus.

It is another object of this invention to provide television apparatus having a picture tube and cabinet therefor with a depth less than the length of the tube, in which means in the cabinet are adapted to support the tube in a substantially longitudinal operating position for direct viewing and in a rest position entirely out of sight within the confines of the cabinet.

Another object of this invention is to provide television apparatus including a shallow cabinet for a scanning tube in which the tube is sup-

ported to provide for the projection of the picture screen during operation of the apparatus from the front of the cabinet and for the moving of the entire tube within the confines of the cabinet when the apparatus is not in use.

A still further object of this invention is to provide television apparatus including a shallow cabinet and a scanning tube which is pivotally supported in the cabinet to provide for an angular swinging of its picture screen during operation in an arc outwardly from the front of the cabinet, and for a positioning of the tube entirely within the cabinet when the television apparatus is not in use.

15 A feature of this invention is to provide a cabinet for television apparatus including a scanning tube of elongated type, which is shallow, has substantially integrally assembled top and side portions to provide for an overall rigid construction, is relatively inexpensive in cost, and is cooperatively assembled with means for supporting the scanning tube to provide for a substantially longitudinal operating position of the tube with its picture face at the front of the cabinet 20 and for a substantially vertical rest position thereof entirely within the confines of the cabinet.

25 A further feature of this invention is found in the provision of a shallow cabinet for television apparatus including an elongated type picture unit, which has a compartment for the unit provided with an open side at the front of the cabinet and means in the compartment for pivotally supporting the picture unit so that the picture screen thereof is pivotally movable across 30 such open side in an arc projected outwardly from the front of the cabinet. A cover for the open compartment side is carried by the picture unit for closing the same when the unit is pivotally moved to a rest position entirely within the compartment.

35 Yet another feature of this invention is found in the provision of television apparatus including picture means having a cabinet and means in the cabinet releasably supporting the picture means therein to provide for the assembly and removal of the same from the cabinet as a complete unit.

40 Further objects, features and advantages of this invention will become apparent from the following description when taken in connection with the accompanying drawings in which:

45 Fig. 1 is a front view of a cabinet for television and radio receiving apparatus showing the picture means in an operating position;

50 Fig. 2 is a side view of the cabinet in Fig. 1

showing the picture means in an operating position corresponding to that in Fig. 1, with parts of the cabinet being removed for the purpose of clarity;

Fig. 3 is illustrated similarly to Fig. 2 and shows the picture means with a cooperating lens for the picture screen;

Fig. 4 is a front view of the cabinet showing the idle or rest position for the picture means;

Fig. 5 is a fragmentary detail view looking at the picture means from the rear as viewed in Fig. 4;

Fig. 6 is a fragmentary view of the means for supporting the picture means in the cabinet; and

Fig. 7 is a view looking toward the left as seen in Fig. 6.

Referring to the drawings there is shown in Figs. 1 and 2 a relatively shallow cabinet 10 for housing both television and radio receiving apparatus in end compartments arranged behind the front control panels 11 and 12, respectively. These panels 11 and 12 may be covered by doors 13 and 14, respectively. Intermediate the above-mentioned two compartments is a compartment 16 for receiving a scanning or picture unit 17 for the television apparatus. The intermediate compartment 16 is separated from the two end compartments by abbreviated side wall members 18 (Figs. 2 and 5) which extend in a vertical direction transversely of the cabinet 10. The side 19 of the compartment 16 at the front of the cabinet is completely open, with the top 21 of such compartment being also common to the end compartments and suitably secured to the cabinet side members 22 and back wall 23. It is evident, therefore, that the top 21 of the cabinet does not function as an ordinary lid or cover but cooperates with the other fixed frame portions of the cabinet to provide in all a cabinet structure which is rigid and rugged and capable of easily and solidly supporting therein the combined weight of the television and radio receiving apparatus.

The picture unit 17 in the compartment 16 comprises a picture tube 24 (Fig. 2) having a length greater than the depth of the cabinet 10. The tube 24 includes a picture face or screen 26 at one end thereof, and a base or electrical connecting portion 27 at the other end adapted for mating electrical engagement with a socket or the like (not shown) provided at one end of a cable the opposite end of which is connected to a suitable power supply for the tube 24. The scanning coil 28 for the tube 24 is located intermediate the picture screen 26 and the connector portion 27. The picture or scanning tube 24 is supported in a mounting structure including side members 29 (Figs. 5, 6 and 7) and a base portion 31. Each side member 29 is provided with an axis member 32 which is fixed thereon in a usual manner by means of cooperating cup members 33.

The axes members 32 are rotatably supported in combination bearing and latching units 36 including an open bearing portion 34 which is mounted on the top of a corresponding one of the wall members 18 for the compartment 16. Each unit 36 is integrally formed with a mounting plate 36 positioned against a side of a wall member 18 and secured thereto as by screws 37. As is clearly evident, from Figs. 6 and 7, the bearing portion 34 is bent substantially normal to the mounting plate 36. Each axis or pivot 32 is releasably retained in a corresponding bearing portion 34 by means of a latch member 38 piv-

totally supported at one end on the mounting plate 36 by axis means 39 and having an enlarged portion 41 at its other end formed with an arcuate section 42 adapted for mating engagement with an axis 32. Thus referring to Fig. 6 when the latching member 38 is in a latching position, the arcuate section 42 closes the open bearing portion 34 to releasably lock the axis member 32 in such bearing. The latch member 38 is yieldably maintained in a latching position by a tension spring 43 connected at one end to a lug 44 on the mounting plate 36, and at its other end to a lug 45 on the latch member 38. The pivotal movement of the latching member 38 to a latching and releasing position relative to the pivot member 32 is defined by the sliding engagement of a pin element 46 carried by the latch in an arcuate slot 47 formed in the mounting plate 36. It is evident, therefore, that the extent of pivotal movement of the latch 38 is limited by the length of the arcuate slot 47.

In the assembly of the picture unit 17 in the cabinet 10 the unit is inserted in the compartment 16 through the open side 19 thereof with the screen 26 toward the front of the cabinet and with each axis member 32 positioned on a corresponding one of the side members 18 of the compartment 16. The entire unit is then slidably moved toward the rear of the cabinet until the axes 32 drop into their corresponding bearing portions 34. As the axes or pins 32 approach the bearing portions 34 they engage and move the latch members 38 away from a closing position relative to the bearing portions 34, against the tension of the springs 43. Thus on dropping of the pins 32 into the bearing portions 34, the latching members 38 are immediately returned to a latching or bearing closing position by the springs 43. When the unit 17 is removed from the cabinet, the latching members 38 are first moved away from a bearing closing position and the unit 17 then lifted from the bearings 34 and slidably moved forwardly of the cabinet on the side walls 18. It is seen, therefore, that the unit 17 is inserted into the cabinet 10 as a unit through the open side 19 of the compartment 16 and is releasably supported therein to facilitate its removal and assembly for service and manufacturing purposes. In its assembled position, and as shown best in Fig. 2, the picture unit 17 is supported for pivotal movement in the compartment 16 to provide for an angular swinging of the picture screen 26 in a vertical direction across the open side 19 of the compartment 16. The pivotal support 32-34 for the unit 17 is arranged relative to the height of the compartment 16 so that the picture tube 24 is movable to a substantially longitudinal position to fully expose the picture screen 26 at the front of the cabinet 10.

As previously mentioned, the cabinet 10 is of a relatively shallow construction, and the tube 24 may be about two feet long, which length is appreciably longer than the depth of the usual cabinet now used for console radios and contemplated for use with television apparatus. Thus when the picture tube is in a longitudinal position, as when the television apparatus is in operation, the picture screen is projected forwardly from the cabinet (Fig. 2) for direct viewing. With the picture screen 26 at the front of the cabinet and also projecting outwardly from the cabinet, the area before the cabinet within which the screen can be easily and comfortably viewed is appreciably increased. Also by virtue

of the angular swinging of the picture screen vertically across the open side 19 of the compartment, adjustment of the screen is accomplished to provide for a positioning thereof at a desired height for viewing by persons seated before the cabinet. The retention of the screen 26 in a desired adjusted position is obtained by means including counterweights 47 carried on the mounting structure for the picture unit at the end thereof opposite the picture screen 26. The weights are of a predetermined size and adapted to cooperate with the frictional resistance at the bearings 34 to maintain the picture unit 17 stationary at any set position. It is evident of course that when the picture unit is not adjustable, the weights 47 can be eliminated and suitable means provided to lock the unit in its rest and operating positions.

When the television apparatus is not in operation the unit 17 is swingable downwardly from its substantially longitudinal position shown in Fig. 2 with a portion projecting from the cabinet 10 to a substantially vertical position shown in Figs. 4 and 5 completely within the compartment 16 and entirely within the confines of the cabinet 10. The wall portion 48 of the mounting structure for the picture unit 17, which is arranged opposite the base portion 31 and is substantially coextensive in length with the tube 24, constitutes a cover or lid for the open side 19 of the compartment 16. Thus as the unit 17 is pivotally moved to a substantially vertical position, the cover 48 is moved into a position for closing the side 19 and hence the compartment 16. As is clearly shown in Fig. 4, the cover 48 in its closing position forms a part of the front of the cabinet 10. Thus when the television apparatus is not in operation, the entire picture unit 17 is completely enclosed within the cabinet so as to entirely hide from view the unsightly picture screen 26 without in any way providing for an increase in the depth of the cabinet 10. A large and bulky cabinet is thus entirely eliminated, while permitting the picture tube to operate in a longitudinal position with the picture screen 26 easily and comfortably visible at the front of the cabinet.

In some instances of installation, it is desirable that the picture or representations on the picture screen 26 be enlarged by a cooperating lens or the like. An assembly of the picture unit 17 including a lens 49 arranged in a cooperating relation with a picture tube 24' is illustrated in Fig. 3. As shown the overall length of the unit 17' is substantially the same as the overall length of the unit 17 because of the tube 24' being somewhat shorter than the tube 24 but having a somewhat wider scanning angle. However, it is obvious that the tubes 24 and 24' may be of the same length and the unit 17' increased to a length greater than the unit 17. This increase in the length of the unit 17' is readily accommodated by the compartment 16 by increasing the length thereof in a direction downwardly of the cabinet 10 an amount corresponding to the increase in the length of the unit 17'. It is seen, therefore, that the housing and supporting of the picture unit for direct viewing thereof from the front of the cabinet, and the complete confinement thereof within the cabinet when it is not in operation, is accomplished equally well with a picture tube alone or with a picture tube in combination with a cooperating lens.

From a consideration of the above description and drawings it is seen that the invention pro-

vides for television apparatus including picture or scanning means and a cabinet therefor of a depth less than the length of said unit having means therein supporting the tube so that the screen thereof is clearly visible from the front of the cabinet when the television apparatus is in operation, and adapted to move the picture unit entirely within the confines of the cabinet when the television apparatus is not in operation. The picture unit is releasably supported for complete removal and assembly in the cabinet at one time, and in its assembled position is adjustable to a plurality of operating positions. The projecting of the picture screen from the front of the cabinet, when the television apparatus is being operated, improves the visibility of the picture screen over an increased radius in front of the cabinet while its complete retraction within the cabinet when it is not being used and the covering thereof by a front portion of the cabinet materially improves the overall appearance of the cabinet.

Although the invention has been described with reference to a specific embodiment thereof, it is to be understood that it is not to be so limited, since modifications and alterations can be made therein which are within the full intended scope of the invention as defined by the appended claims.

30 I claim:

35 1. A cabinet for television apparatus including a picture unit with a viewing portion, said cabinet having a front side and said unit having an overall length greater than the depth of said cabinet, and means movably supporting said picture unit in said cabinet such that said picture unit is movable to a rest position entirely within the confines of the cabinet, and movable to an operating position with said viewing portion extending outwardly from the front side of said cabinet.

40 2. A cabinet for television apparatus including a picture unit with a picture screen, said cabinet having a front side with an open portion therein, and said picture unit having an overall length greater than the depth of said cabinet, and means supporting said unit for pivotal movement transversely of said cabinet and in a substantially vertical plane to provide for the angular moving of said picture screen over the open portion of the front side of said cabinet, said picture screen when the picture unit is in a substantially longitudinal position projecting outwardly from said cabinet front side, and said unit when in a substantially vertical position being enclosed entirely within the confines of said cabinet.

45 3. A cabinet for television apparatus including a picture unit having a picture screen at one end and a wall portion at one side thereof, with the overall length of said picture unit being greater than the depth of said cabinet, said cabinet having a front side and a compartment therein open at said cabinet front side for receiving said picture unit, and means pivotally supporting said picture unit in said compartment to provide for an angular movement of said picture screen vertically of said cabinet across said compartment opening, with said picture screen in operating position projecting outwardly from the front side of said cabinet, and in a rest position being arranged entirely within said compartment, said wall portion when said picture screen is in said rest position completely closing said compartment opening.

50 4. In television apparatus including a picture unit, a cabinet with a front side having a com-

partment therein open at said front side, said compartment having spaced side walls extending transversely of said cabinet, said picture unit being adapted to be received in said compartment and having a picture screen at one end and weight means at the other end thereof and a wall portion extending between said two ends, said picture unit having an overall length greater than the depth of said cabinet axis means extending transversely of said picture unit intermediate said two ends, and frictional bearing means on said compartment side walls for receiving said axis means to provide for the pivotal swinging of said picture screen vertically across the compartment opening at the front of said cabinet, with said weight means and bearing means cooperating to retain said picture screen in any desired operating position at said compartment opening, said picture screen in an operating position projecting outwardly from said cabinet front side, and said wall portion on pivotal movement of said picture unit within said compartment closing said compartment opening.

5. In television apparatus including a picture unit, a cabinet having a compartment therein with an open side at the front of said cabinet and abbreviated vertical side walls extending transversely of said cabinet and spaced laterally thereof, combination bearing and latch means mounted on the top of each of said side walls including an open bearing portion and a spring actuated pivoted latch movable to close said bearing portion, said picture unit being adapted to be received in said compartment through said open side and including a picture tube having a picture screen near one end thereof, said picture unit having an overall length greater than the depth of said cabinet, and axis means on said picture unit rotatively supported in said bearing portions and releasably retained therein by said spring actuated latches, said axis means being slidable on the tops of said wall portions to said rotatably supported position to provide for the removal and assembly of said picture unit through the open side of said compartment, said picture screen when said picture tube is in a substantially longitudinal position extending through said open compartment side and outwardly from the front of said cabinet, and said unit when said picture tube is in a substantially vertical position being arranged entirely within the confines of said compartment.

6. In television apparatus including a picture unit, a cabinet having a compartment therein with an open side at the front of the cabinet and vertical side walls extending transversely of said cabinet, said picture unit being adapted to be received in said compartment and including a picture tube having a picture screen near one end thereof, said picture unit having an overall length greater than the depth of said cabinet, and axis means on said unit rotatably supported on said compartment side walls to provide for a rotary movement of said unit in a substantially vertical plane, said picture screen when said tube is in a substantially longitudinal position extending through said open compartment side outwardly

from the front of said cabinet, and said unit when said picture tube is in a substantially vertical position being arranged entirely within the confines of said compartment.

7. A cabinet for television apparatus including picture means, said cabinet having a compartment with an open side at the front of said cabinet and a pair of side walls extending transversely of the cabinet and spaced laterally thereof, said picture means being adapted to be received in said compartment and having a picture screen at one end thereof, said picture means having an overall length greater than the depth of said cabinet, means pivotally supporting said picture means on said side walls to provide for a pivotal movement of said picture screen across said open side, and a cover for said open side carried by said picture means, said cover when said picture means is in said compartment closing said open side and forming a part of the front of said cabinet.

8. In television apparatus including picture means with a picture screen near one end thereof, a cabinet having a front side with an open portion therein, and said picture means having an overall length greater than the depth of said cabinet, means pivotally supporting said picture means in said cabinet so that said picture screen is pivotally movable in a substantially vertical plane across said open portion, and a cover for said open portion carried by said picture means, said picture means when said picture screen is in an operating position having a portion thereof projecting outwardly from said cabinet, and said picture means when said picture screen is in a rest position being positioned entirely within the confines of said cabinet with said cover closing the open portion in the front side of said cabinet.

9. In television apparatus including picture means having a picture tube with a screen and a cooperating lens at one end and an electrical connecting portion at the other end, a cabinet with a front side having a compartment for receiving said picture means, said compartment having an open side at the front of said cabinet, and vertical side walls extended transversely of the cabinet and spaced laterally thereof, said picture means having an overall length greater than the depth of said cabinet, axis means on said picture means intermediate said two ends, combination bearing and releasable locking means on each of said side walls rotatably supporting said axis means but permitting removal and assembly of said picture means as a unit through said open compartment side, with rotation of said picture means in said compartment angularly moving said picture screen in a substantially vertical plane across said open compartment side, said picture screen and cooperating lens when said picture tube is in a substantially longitudinal position projecting forwardly from the front of said cabinet, and a cover for said open compartment side carried by said picture means, said picture means when said picture tube is in a substantially vertical position being arranged completely within the confines of said compartment with said cover in a closing position over the open side thereof.

RAYMOND S. YODER.
